United States Patent Office

Des. 214,594
Patented July 1, 1969

214,594

PORTABLE VIEWFINDER FOR CINEMATOGRAPHY OR THE LIKE

Jimmie D. Songer, Los Angeles, Calif., assignor to Video West, Inc., Beverly Hills, Calif., a corporation of California

Filed May 22, 1968, Ser. No. 12,041

Term of patent 14 years

Int. Cl. D16—07

U.S. Cl. D61—1

FIG. 2.

FIG. 3.

FIG. 4.

FIG. 5.

FIG. 6.

FIG. 1 is a top plan view of a portable viewfinder for cinematography showing my new design, with a camera lens shown in dotted outline disconnectably mounted thereon;

FIG. 2 is a side elevational view thereof;

FIG. 3 is a front end view thereof with the camera lens omitted;

FIG. 4 is a side elevational view thereof, taken from the side opposite that seen in FIG. 2;

FIG. 5 is a bottom view thereof; and

FIG. 6 is a rear end view thereof.

The dominant features of my design reside in those portions shown in full lines.

I claim:

The ornamental design for a portable viewfinder for cinematography or the like, substantially as shown and described.
